(57) **CLAIM**

The ornamental design for a rocker switch, as shown and described.

DESCRIPTION

FIG. 1 is an elevated perspective view of the rocker switch from above, showing the new design;

FIG. 2 is an elevated perspective view of the rocker switch from below;

FIG. 3 is a top view thereof;

FIG. 4 is a bottom view thereof;

FIG. 5 is a side view thereof; and,

FIG. 6 is an end view thereof.

The broken line showing of the environment is for illustrative purpose only and forms not part of the claimed design.
